[57] **CLAIM**

The ornamental design for a plate or similar article, as
shown and described.

DESCRIPTION

FIG. 1 is a top plan view of a plate or similar article
showing my new design;
FIG. 2 is a side elevational view thereof, with all sides
being similar;

FIG. 3 is a bottom plan view thereof; and

FIG. 4 is a vertical cross-sectional view thereof, taken
along line 4—4 of FIG. 1, looking in the direction of the
arrows.

FIG. 1.**FIG. 2.****FIG. 3.****FIG. 4.**
